FOOD CARTON

Derek Fallowfield, Oakville, Ontario, William Henry Day,
Brantford, Ontario, and Stanley Tooke, Burlington,
Ontario, Canada, assignors to W. R. Grace & Co.,
Duncan, S.C.

Filed Dec. 14, 1971, Ser. No. 208,050

Term of patent 14 years

Int. Cl. D9—03

U.S. Cl. D9—182

FIG. 2

FIG. 3

FIG. 4

FIG. 5

FIG. 6

FIG. 1 is a perspective view of a food carton showing our new design;

FIG. 2 is a top plan view on a reduced scale showing the food carton in an open position;

FIG. 3 is a side elevational view thereof;

FIG. 4 is a front elevational view on the same scale as FIGS. 2 and 3 showing the food carton in a closed position;

FIG. 5 is a side elevational view thereof; and

FIG. 6 is a rear elevational view thereof.

We claim:

The ornamental design for a food carton, substantially as shown.
